UNITED STATES PATENT OFFICE.

GEORGE FOX, OF WICHITA, KANSAS.

INTAKE-MANIFOLD.

1,347,807.

Specification of Letters Patent.

Patented July 27, 1920.

Application filed September 8, 1919. Serial No. 322,467.

To all whom it may concern:

Be it known that I, GEORGE FOX, a citizen of the United States, residing at Wichita, in the county of Sedgwick and State of Kansas, have invented a new and useful Intake-Manifold, of which the following is a specification.

This invention relates to intake manifolds for automobiles, one of its objects being to provide a device adapted to be substituted for the manifold ordinarily employed and which can be utilized as a means for preheating the gas prior to the starting of the motor, thus to facilitate the starting, especially in cold weather.

A further object is to provide means whereby heated air can be supplied in desired amounts, said air being heated by the exhaust after the engine has been started.

20 A still further object is to provide means for supplying moisture to the mixture thereby to render it more efficient.

25 A further object is to provide a device of this character which can be substituted readily for the ordinary manifold.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of parts without departing 35 from the spirit or sacrificing any of the advantages of the invention as set forth in the appended claims.

In the accompanying drawings the preferred form of the invention has been shown.

40 In said drawings—

Figure 1 is a side elevation of the device parts being broken away and the slidable burner being shown, by dotted lines, in extended position.

45 Fig. 2 is an end elevation.

Fig. 3 is a transverse section through the slidable burner.

Fig. 4 is a detail view showing the latch of the slidable burner.

50 Referring to the figures by characters of reference, 1 designates the stem of the intake manifold and 2 the arms thereof, there being the usual clamps shown generally at 3 and the exhaust manifold shown at 4. The carbureter 5 opens into the stem 1 as ordi-

narily and is provided with the usual gas intake.

Fitted around the stem 1 and the lower portions of the arms 2 of the intake is a casing 6 the top of which is connected to a hot air intake pipe 7 terminating in an elongated hood 8 which extends along and lies close to although spaced from the exhaust manifold so that when said manifold is heated it will also heat the thin sheet of air drawn into the hood 8 by the suction of the engine.

A tubular extension 9 projects from the casing 6 and is adapted to receive one end of a gooseneck 10 the other end of which is insertible into the air inlet of the carbureter and is held therein by a pin 11 insertible through the extension 9 and one end of the gooseneck.

The bottom of the casing 6 is open and provided with parallel sides 12 to which are connected guide cleats 13 and supported by and under these cleats is a slidable closure 14 divided by a partition 15 into a water receptacle 16 and a wick holder 17. The wick holder has tubes 18 extending upwardly from the bottom thereof for supplying air and the wick 19 saturated with alcohol or other fuel is adapted to lie within the holder and around the tubes. Spaced notches 20 are formed in the side of the closure and either of them is adapted to receive a spring catch 21 so that the closure will thus be held in either of two positions.

Mounted within the extension 9 is a butterfly valve 22 and an arm 23 extends from the stem of this valve and is connected by a rod 24 to one end of the closure 14. A cover 25 is hingedly connected to the casing 6 and is adapted to lie on the projecting portion of the closure 14 and shut it when positioned as shown by dotted lines in Fig. 1.

In using the device herein described the wick is saturated with alcohol or the like, it being understood that the closure is normally in the position indicated by dotted lines in Fig. 1 and that it is then possible to saturate the wick simply by raising the cover 25 and pouring the fuel onto the wick. When the closure is in this normal or extended position the valve 22 is open. In starting the engine the fuel is ignited and the closure 14 is then slid to position across the open lower end of the casing 6. During this movement of the closure the rod 24 will 110

shift the valve 22 to closed position to prevent the hot products of combustion from entering the carbureter. The burning fuel will heat the stem and arms of the manifold 5 and the gas when sucked therewith by the pistons of the engine will be quickly vaporized and insure the starting of the motor. Before the engine is started, the closure 14 is pulled out to its normal or extended position and the cover 25 is lowered thereonto to extinguish the flame. This will bring the water receptacle 16 to position under the casing 6 and the vapor arising therefrom will mix with the air in the casing and flow 10 therewith to the carbureter by way of the gooseneck 10, the valve 22 being opened by the movement of the closure 14 to extended position. Air is supplied to the casing 6 through the hood 8 and pipe 7 and as it is 15 taken from the hot surface of the exhaust manifold it will be in a highly heated condition after the engine has once started. The catch 21 will hold the closure in either of the two positions to which it may be moved.

25 What is claimed is:—

1. The combination with the carbureter, intake manifold and exhaust manifold of an engine, of a casing housing a portion of the intake manifold, means for supplying air 30 thereto from the outer surface of the exhaust manifold, means for directing heated air from said casing to the carbureter, a burner movable into and out of position under the casing, and means operated by 35 the movement of said burner into and out of position under the casing for closing and opening communication, respectively, between the casing and the carbureter.

2. The combination with the carbureter, 40 intake manifold and exhaust manifold of an engine, of a casing housing a portion of the intake manifold, a means for supplying air to the carbureter from the casing, a valve controlling said means, a burner movable 45 into and out of communication with the interior of the casing, and means operated by the movement of the burner to open and close the valve.

3. The combination with a carbureter, 50 intake manifold and exhaust manifold of an engine, of a casing housing a portion of the intake manifold, a valved connection between the casing and the carbureter, means for conducting heated air from the exterior

surface of the exhaust manifold to the casing, a burner movable into and out of communication with the interior of the casing, and means operated by the movement of the burner for actuating the valve in the connection. 60

4. The combination with a carbureter, intake manifold and exhaust manifold of an engine, of a casing housing a portion of the intake manifold, means for conducting thereto heated air from the surface of the exhaust manifold, means for conducting air from the casing to the carbureter, a valve, a combined water receptacle and burner constituting a closure for the bottom of the casing, the burner being movable into and 70 out of position under the casing, and means operated by the movement of said receptacle and burner for opening and closing the valve.

5. The combination with a carbureter and 75 intake manifold of an engine, of a casing housing a portion of the manifold, means for conducting air from the casing to the carbureter, a valve in said means, a closure 80 movably connected to the bottom of the casing and including a water receptacle and a burner, said closure being movable to bring the burner into or out of communication with the interior of the casing, a cover for the burner when out of communication with 85 the interior of the casing, and means operated by the said closure for opening the valve and for closing it.

6. The combination with the carbureter and intake manifold of an engine, of a casing housing a portion of the manifold and having an air inlet, means for conducting air from the casing to the carbureter, a valve in said means, a closure for the bottom of the casing and having a water container and 90 a burner, said closure being movable to place the burner in or out of communication with the interior of the casing, means for fastening the closure in either of said positions, and means for transmitting motion to the 100 valve from the closure.

In testimony that I claim the foregoing as my own, I have hereto affixed my signature in the presence of two witnesses.

GEORGE FOX.
